UNITED STATES PATENT OFFICE.

NIELS WALTERSEN AASEN, OF COPENHAGEN, DENMARK.

SAFETY DEVICE FOR SHELLS.

1,214,253.

Specification of Letters Patent. Patented Jan. 30, 1917.

Application filed November 18, 1915. Serial No. 62,161.

To all whom it may concern:

Be it known that I, NIELS WALTERSEN AASEN, a citizen of the Kingdom of Norway, residing at No. 20 Carl Lunds Gade, Copenhagen, Denmark, have invented new and useful Improvements in or Relating to Safety Devices for Shells, of which the following is a specification.

This invention relates to a safety-device 10 for shells, particularly inflammable shells and small bursting shells, which are shot from small howitzers, mortars or the like.

One form of construction of a shell, provided with the safety-device herein referred 15 to, is shown in the drawing, in which—

Figure 1 is a side elevation (partly in section) and Fig. 2 is a rear end view.

The shell consists of the shell-casing 1 with, for instance, a four-winged steering tail-piece 2, made of aluminum. The firing mechanism consists of a hollow screw 3, which is screwed into the apex of the shell, and which receives a firing-pin 4 furnished with an impact-plate 40, which firing-pin is held fast 25 to the hollow screw 3 by means of a spiral spring 5 and actuates the detonator 10 when the shell strikes. The safety-device consists of a safety-pin 7 disposed in a tube 6 which passes longitudinally through the shell. To 30 the rear end of said safety-pin 7 there is attached a screen or plate 9 of thin and light metal, paper, pasteboard, cloth (in which case it is given the shape of a parachute) or the like, while its front end carries a detachable and loosely fastened safety-piece 8, which prevents the untimely striking of the firing-pin on the detonator 10. When the safety-piece 8 is released from the pin 7, it will, owing to its lower oblique edge, slide 35 outward of its own accord when the impact-plate 40 strikes an obstacle at the impart of the shell.

Instead of a single safety-piece, there may be two, one on either side of the shell and 40 hinged to each other, the pin 7 constituting the hinge-bolt for both of them. The safety-piece may also be circular and held together by means of the safety-pin.

When the shell is discharged, the air-pres- 45 sure on the plate 9 will hold it back, thereby pulling out the pin 7, while the shell is pass-

ing the first ten or twelve meters of its trajectory. The firing mechanism is then set, or exposed, and will cause the shell to explode as soon as it strikes.

55

If the shell is dropped during transportation or in loading, the firing-mechanism will not operate, since the pin 7 cannot be drawn out except when the shell has a very great speed.

60

When a screen or parachute of cloth, or the like, is used instead of the plate 9, it may be disposed between two of the wings 2 of the tail-piece, so that, immediately after the shell is discharged, the parachute will expand and pull out the safety-pin.

65

I claim:

1. In a shell, a firing pin at the front part thereof, a plate attached to said firing pin, a safety pin having a projection at the front 70 of said shell and adjacent the said plate, a safety piece loosely carried upon said safety pin and intermediate said plate and the front of the shell, and means for automatically retracting said safety pin when the said shell 75 is propelled.

2. In a shell, a firing pin at the front part thereof, a plate attached to said firing pin, a safety pin having a projection at the front 80 of said shell and adjacent the said plate, a safety piece loosely carried upon said safety pin and intermediate said plate and the front of the shell, said safety piece having an oblique edge adjacent said shell, and means for automatically retracting said safety pin 85 when the said shell is propelled.

3. In a shell, a firing pin at the front part thereof, a plate on said firing pin, a movable safety piece intermediate the said plate and the front of said shell and preventing the 90 forcing in of said firing pin, and means for automatically releasing said safety piece after the shell has been propelled, said means being operated by a pressure caused by the movement of said shell.

95

In testimony that I claim the foregoing as my invention, I have signed my name in presence of two subscribing witnesses.

NIELS WALTERSEN AASEN.
